CARBURETOR

Emmett K. Chaffin, Fort Myers, Fla.

Application January 3, 1940, Serial No. 312,287

1 Claim. (Cl. 261—18)

My invention relates to improvement in carburetors and more particularly to dual carburetors so-called.

The invention is designed with the particular object in view of providing a unitary, dual carburetor of practical, inexpensive construction and a high degree of efficiency adapted for selective use under control of a single simplified valve to supply carbureted fuel either from a common fuel tank or from two separate tanks, as desired, and whereby carburetor failure particularly in airplane power plants may be obviated.

To the accomplishment of the above, and subordinate objects presently appearing, a preferred embodiment of my invention has been illustrated in the accompanying drawings, set forth in detail in the succeeding description, and defined in the appended claim.

In said drawings:

Figure 1 is a view in side elevation of the preferred embodiment of my invention.

Figure 2 is a view in end elevation.

Figure 3 is a view in vertical longitudinal section, and

Figure 4 is a view in horizontal section taken on the line 4—4 of Figure 3 looking downwardly and indicated by the arrows.

Referring to the drawings by numerals, the illustrated embodiment of my invention comprises, as its basic element, a main, substantially tubular, upright section 1 having a closed bottom 2 and forming a mixing chamber 3, a pair of cup-like sections 4 at diametrically opposite sides of the section 1, respectively, having bottoms 5 preferably dropped below the bottom 2, and forming a pair of float chambers 6, a pair of upper side extensions 7 on the sides of the sections 4, respectively, in the plane of the said sections 1 and 4 and forming valve chambers 8 opening into the float chambers 6, a lateral, main air inlet conduit 9 at the bottom of the main section 1, intermediate the sections 4, and a pair of cover plates 10 detachably secured by screws 11 to the tops of the sections 4.

The main section 1 is provided in the top thereof with the usual type of butterfly throttle valve 12. The bottom 2 of the main section 1 is provided with a diametrical bore 13 therein opening into the bottoms of both float chambers 6 and forming, as will presently more clearly appear, a valve casing. A pair of fuel discharge ports 14 are provided in the bottom 2 of section 1 at diametrically opposite sides thereof, and adjacent to the float chambers 6, respectively, in

the line of the bore 13 and leading upwardly from said bore. A pair of nozzle-type, main inlet jets 15 are threaded at the lower ends thereof into the ports 14, respectively, to extend therefrom up into the mixing chamber 3, said jets converging toward the axis of said chamber into close proximity at the upper ends thereof. A sleeve 16 of hour-glass form fitted into the section 1 and secured therein between the conduit 9 and valve 12 provides a restricted throat above 10 said jets 15 and conduit 9 for facilitating mixing the spray from the nozzles 15 with the air in the mixing chamber 3. One of the discharge ports 14 and the main jet 15 thereof are related to each of the float chambers 6 for a purpose presently apparent.

Idling jets are provided in the form of a pair of ducts 17 in the wall of the section 1 extending downwardly side by side in a vertical boss on said section from the top of said boss and 20 through the bottom 2 of the section 1 into the ports 14, respectively, beneath the jets 15, said jets, or ducts 17 being suitably arranged at the upper ends thereof for the entrance of air thereinto. A single air adjustment 19 controls air 25 mixture for idling, regardless of which idling jet is furnishing fuel.

A pair of gasoline feed lines 20 are connected to the bottoms of the needle valve chambers 8 by couplings 21 and nipples 22, said nipples opening into vertical inlet ports 23 provided in the bottoms of said chambers. A pair of needle valve seats 24 are threaded downwardly into the bottoms of the needle valve chambers 8 in registration with the ports 23, respectively. A pair 35 of suitable floats 25 in the float chambers 6, respectively, are pivotally mounted therein, as at 26, and operatively connected as at 27 to vertically slideable needle valves 28 in said chambers 8, said valves coacting with the seats 24 in the usual 40 manner and under control of the floats 25 to control the level of the gasoline in their related float chambers 6. Feed lines 20 may be connected to the main supply tank of the power plant, or, one to said tank and the other to an auxiliary 45 tank, neither tank being shown.

A rotary tubular valve 29 is extended through a suitable bearing boss 30 provided on the sections 4, and through the float chamber 6 of said section and the bore 13 into the other float chamber 6, 50 said valve having an outer end extending out of said boss 30 and equipped with a crank 31 to which a suitable operating rod 32 is pivoted. A set screw 33 extended through the boss 30 into a circumferential groove 34 in said valve 29 blocks

endwise movement of the valve. The bore 35 of the valve 29 has an inner, radially ported end, as at 36, opening into one float chamber 6 and is partitioned transversely, as at 37, intermediate 5 the discharge ports 14 so that its inner end opens into the other float chamber 6, but is closed off from the first mentioned float chamber. A pair of radial ports 38 are provided in said valve upon diametrically opposite sides thereof and upon 10 opposite sides of the partition 37, said ports 38 being disposed to register with the discharge ports 14, respectively, under an 180 degree turn of the valve 29 in opposite directions. A pair of drain plugs 39 are threaded into the bottom 2 15 of the section 1 in the path of rotation of said ports 38 for draining the valve 29 of sediment.

The operation of my invention will be readily understood. The main section 1 is connected at its top, in the usual manner, to the intake manifold of the engine, not shown. By rotating the valve 29 in opposite directions through an arc of 180 degrees, either port 38 of said valve 29 may be registered with the related port 14 to establish communication between a selected float chamber 25 6 and the related main jet 15, together with the associated idling port 17 so that if one side of the carburetor fails the other side may be resorted to. The manner in which the spray or vapor issuing from the main jets 15 and idling 30 jets 17 mixes with the air in the mixing chamber 3 will be readily apparent and need not be entered into herein.

The foregoing will, it is believed, suffice to impart a clear understanding of my invention without further explanation.

Manifestly the invention, as described, is susceptible of modification without departing from

the inventive concept and right is herein reserved to such modifications as fall within the scope of the subjoined claim.

What I claim is:

In a dual carburetor, an upright main tubular 5 section forming a mixing chamber and having a diametrically bored bottom, a pair of main jet members upstanding from said bottom at diametrically opposite sides thereof and opening at the lower ends thereof into the top of said bore 10 upon opposite sides of the transverse center of the latter, a pair of float chamber sections extending from opposite sides of said main section for connection to separate sources of similar fuel supply, respectively, and communicating with 15 opposite ends of said bore, respectively, and a tubular valve member rotatably fitted in said bore and extending into both said float chamber sections in communication therewith, said valve member being partitioned transversely 20 intermediate said jet members and provided with a pair of diametrically opposite radial ports therein upon opposite sides of said partition, respectively, whereby under rotation of said valve member through 180° of movement in opposite 25 directions said ports may be registered with said jet members, respectively, to selectively connect said float chamber sections with said jet members, respectively, and means to rotate said valve member, the main section having a pair of ducts 30 therein forming idling jets and extending downwardly through the wall of the section and across the bottom thereof and having lower ends communicating with the lower ends of said main jet members respectively.
